Primary Examiner — Daniel Bui*(74) Attorney, Agent, or Firm* — Maine Cernota & Rardin**CLAIM**

The ornamental design for a plug for tool-releasable solar power connector, as shown and described.

DESCRIPTION

FIG. 1 is a front view of a plug for tool-releasable solar power connector, showing our new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front, top perspective view thereof; and,

FIG. 8 is a back, bottom perspective view thereof.

The broken line portion of the figure drawings is included to show unclaimed subject matter only and forms no part of the claimed design.
